UNITED STATES PATENT OFFICE

HENRY P. WELNA, OF ST. PAUL, MINNESOTA

ADJUSTABLE FASTENER FOR STORM WINDOWS

Application filed January 29, 1929. Serial No. 335,846.

This invention relates to the broad class of closure fasteners and it has more particular reference to a new form of fastener especially adapted for use in connection with a hingedly mounted storm window.

My principal object is to generally improve upon fasteners of this broad class by providing a structure which is more efficient in performance, positive and dependable in action, 10 easy to manipulate, economical, easy to install, practicable in construction, and such as to better fulfill the requirements of an invention of this class.

Other features and advantages of the invention will become more readily apparent from the following description and drawings:

In the drawings:

Figure 1 is a vertical sectional view 20 through the window structure including sliding sashes and a hingedly mounted storm window provided with the improved fasteners showing the fasteners in operative position, the storm window being closed.

Figure 2 is a view like Figure 1, showing the storm window open.

Figure 3 is a view of the complete fastener removed.

Figure 4 is an elevational view of a special 30 guide fixture.

Figure 5 is an elevational view of the quadrant.

Figure 6 is an edge view of the quadrant.

Figure 7 is a transverse sectional view 35 through the slidable guide and retaining fixture therefor.

Figure 8 is a view of a novel binding nut.

Figure 9 is a perspective view of a storm 40 window attaching bracket.

In Figure 1, the reference character 10 designates generally the window frame, 11 the lower sliding sash, 12, the upper sliding sash, and 13 a vertically swingable storm window mounted upon the frame and disposed in spaced relation to the sashes 11 and 12.

The improved fastener comprises arcuate slotted quadrants 14, whose offset end 15 is pivotally connected to an attaching bracket 50 16. This attaching bracket is fastened to the

frame of the storm window. The opposite end of the quadrant is directed laterally to provide a finger grip 17.

The inner slotted end portion of the quadrant is cooperable with the slide generally 55 designated by the reference character 18 in Figure 8. The slide comprises a rectangular guide block 19 having a screw-threaded stem 20 carrying a retaining nut 21. The retaining nut is threaded on the stem and is provided with a pivotally mounted or hinged finger grip 22 which may be conveniently arranged to facilitate turning of the nut 21.

The slide cooperates with a retaining fixture 23 of the type seen in Figure 4, this being rigidly fastened to the window frame at the position shown. This fixture is of channel shape in cross section and is formed with a block. The block 19 is slidable therein; occupying the position seen in Figure 7 with the threaded end extending through and beyond the slot. This stem also extends through the slot in the quadrant 14 and that portion extending beyond the quadrant carries the retaining nut 21.

When the device is in place, the storm window may be swung to open position or closed position, without interfering with or striking the sash 11. The guide 19 may be adjusted in the fixture 23, to insure proper clearance, as 70 the quadrant swings up and out or in and down.

This fastener permits the storm window to be opened a distance permitted by the length of the quadrant and it does not interfere with the opening and closing of the inside sliding sash, whether the storm window is open part way or only a small amount for ventilation. This desirable action is produced by the presence of the adjustable guide working in the retaining fixture therefor. This fixture being slotted, allows the guide to be moved up and down and the thumbscrew to be tightly fastened to hold the quadrant in any position to which it has been adjusted.

When the storm window is closed, the thumb screw and guide block on which it is carried should be at the top of the slot in the retaining fixture. When, however, the storm window is opened, the block must be at the

bottom of the slot. Otherwise, the quadrant will not clear the inside window sash.

This fastener eliminates rattling and can not be opened from the outside unless the window is opened far enough to allow the person's hand or arm to pass upwardly between the frame and the storm window. These and other advantages and features have doubtless been made apparent from the foregoing description. Therefore, a more lengthy description is regarded as unnecessary.

Minor changes in the shape, size and rearrangement of details coming within the field of invention claimed may be resorted to, in actual practice, if desired.

I claim:

As a new product of manufacture, a storm window fastener of the class described comprising a storm window attaching bracket, an elongated acute slotted quadrant pivotally connected at one end to said bracket, a retaining fixture adapted to be fastened to the window frame, said fixture being of channel shaped cross section and formed with an elongated slot, a guide block slideable in said fixture and including a threaded stem extending through the slot in said fixture and through the slot in said quadrant, and a retaining nut carried by said threaded stem and cooperable with the quadrant to hold the quadrant in different adjusted positions.

In testimony whereof I affix my signature.

HENRY P. WELNA.
